UNITED STATES PATENT OFFICE.

FRANK A. SANDMANN, OF RAHWAY, NEW JERSEY.

METAL FILING-CASE.

1,340,562.

Specification of Letters Patent. Patented May 18, 1920.

Application filed July 2, 1919. Serial No. 308,149.

To all whom it may concern:

Be it known that I, FRANK A. SANDMANN, a citizen of the United States, residing at Rahway, in the county of Union 5 and State of New Jersey, have invented certain new and useful Improvements in Metal Filing-Cases, of which the following is a specification.

My invention relates to metal filing cases 10 such, for instance, as are employed for receiving filing drawers, and for other uses, and especially to filing cases of this character which are arranged to be built up in so-called units.

15 Objects of my invention are to provide a metal filing case, the units whereof comprise separable parts arranged in novel manner to form a knock-down filing case unit arranged to be readily assembled; further, to provide a novel arrangement of 20 parts comprising a filing drawer and members of the filing case unit arranged to be assembled in novel manner, the said members of the filing case unit constructed to 25 be conveniently and readily arranged in knock-down relation in a package of small compass, so that the parts may take up small space and weight in shipment or carriage of the same.

30 Further objects of my invention are to provide sides for the metal units, and cross-pieces for the front and rear ends of the latter, arranged to be releasably connected in novel manner with the sides for assembling the parts in superposed relation; further, to provide a top-member received crosswise of the sides and provided with end-limiting means for limiting the end 35 movements of the drawer received in the unit; further, to provide novel members which comprise a unit and novel means for connecting the members; further, to provide novel means for connecting the units in superposed relation; further, to provide 40 novel means for connecting adjacent stacks of units; and, further, to provide novel constructions and arrangements of parts.

The invention will be further readily understood from the following description 50 and claims, and from the drawings, in which latter:

Figure 1 is a perspective view exemplifying my invention, and showing units which are superposed to form stacks of units, the 55 stacks being arranged side by side, parts of the units being broken away for better

illustration of the construction and arrangements of the parts.

Fig. 2 is a central longitudinal section of my improved device, taken on the line 2-2 60 of Fig. 1, and partly broken away,

Fig. 3 is a cross-section of my improved device, partly broken away, taken on a line corresponding to the line 3-3 of Fig. 2.

Fig. 4 is a perspective view of one of 65 the cross-bars of my improved device.

Fig. 5 is a plan view of the front end of one of the side walls, partly broken away.

Fig. 6 is an inside elevation of the same.

Fig. 7 is a cross-section on the line 7-7 70 of Fig. 5.

Fig. 8 is a horizontal cross-section, taken on a line corresponding to the line 8-8 of Fig. 2, showing the connecting means between adjacent units. 75

Fig. 9 is a detail of the locking connection between superposed units, shown in section on the line 9-9 of Fig. 1.

Fig. 10 is a detail in section on the line 10-10 of Fig. 1; and, 80

Fig. 11 is a perspective view of the connecting plate between superposed units.

The sides of my improved device are represented at 21. These sides are exemplified as duplicates one of the other, comprising a sheet of sheet-metal having its front and rear ends bent to form socket-ends 22, 23, preferably in the form of sheet-metal cylinders, the axes of which are in the median plane of the sheet of metal forming the side. These socket ends form stiffening means for the sheet and sockets for the connecting members hereinafter described. 85

Cross-bars 25 are provided with posts 95 26, 27. The posts extend respectively above and below the cross-bar at the respective ends of the cross-bar. These posts are exemplified as pins at the respective ends of the cross-bar, the pin at each end of 100 the cross-bar being integral and extending above and below the cross-bar, through apertures 28 to form the posts, the pins being securely held in said apertures as by means of being driven thereinto, or, if desired, being brazed or welded in place. 105

The posts extending from the respective upper and lower sides of the cross-bar are received in the bores 30 formed in the ends of the side walls of the unit, the bores forming sockets for the posts. Thus the posts 27, 110 which extend downwardly, are received

within the upper ends of said bores of the side walls of a lower unit, and the upwardly extending posts 26 have the socket ends of the side walls of the unit thereabove received thereover. The posts are at the respective corners of the unit. The fit between said posts and the inner walls of the sockets is preferably a snug fit, so as to maintain the cross-bars and the side walls of the unit in right angular relation when the same have been assembled, and the posts extend a substantial distance into the sockets to prevent tilting of the units in use. Tilting is also prevented as hereinafter described.

15 The cross-bars and posts are located between proximate superposed units, one of the cross-bars, with the posts extending upwardly and downwardly therefrom, being located between the front ends, and one of 20 the cross-bars, with the posts extending upwardly and downwardly therefrom, being located between the rear ends of proximate superposed units.

25 The front ends and the rear ends of the side walls are preferably provided with recesses 33, in which the cross-bars are received, these recesses being shown at the lower ends of the respective curled ends of the side walls.

30 Runways 35 are provided for each of the units when they are intended to receive drawers. A filing drawer is exemplified at 36 as a sheet-metal drawer. The runways are shown as right-angularly bent sheet-metal strips provided with wings 37, 38. The wings 37 are secured to the side walls between the curled ends of the same, the securing being exemplified as accomplished by means of spot welding, such spot-welds 35 being indicated at 39. The wings 38 project laterally from the side walls and are arranged so that the respective side walls of a given unit have said wings 38 projecting toward each other, preferably at right 40 angles to the side walls, for forming shelves for the drawers.

45 Each of the runways is provided with anti-friction means, exemplified as a roller 41. The roller has axles 42. The shelf is provided with an opening 43, the side walls of which are provided with depressions 44 formed up therein for forming bearings for the axles 42 of the roller. A retaining-piece 46 of sheet-metal has an opening 47 struck up therein, the metal of the opening being struck down in the form of flanges 48. The side walls 49 at the respective sides of the opening in the retaining-piece are received over the axles of the roller which 50 have been received in the bearings 44 in the shelf, the flanges 48 extending through the opening 43 in said shelf, as shown in dotted lines in Fig. 7, and being then bent away from each other against the lower 55 faces of said shelf, as shown in full lines in

70 said figure, for fixing said retaining piece in position above the axles of the roller so as to maintain the roller in its bearings. The upright wings 37 of the angle strips are received in the space between the inner portions of the curled ends 22, 23, of the side walls, as shown in Figs. 5 and 6, the respective ends of the laterally extending wings of the runways resting on the respective front and rear cross-bars 25.

75 The drawer is provided with a rear wall 51 and a front wall 52, which respectively preferably extend to approximately the height between cross-bars of superposed units.

80 A top-member 53 is provided for the unit, the top-member comprising a sheet-metal plate having downwardly bent side flanges 54, a downwardly bent rear flange 55, and a downwardly bent front flange, the latter 85 comprising a downwardly bent section 56, a rearwardly bent section 57 extending from the lower end of the latter, and a downwardly bent section 58 extending downwardly from the rear end of the rearwardly bent section 57.

85 The downwardly bent flanges 54 are preferably connected with the upper ends of the side walls between the curled ends thereof, as by means of screws 61 received through 90 previously formed registering holes 62, 63, respectively in the upper ends of the side walls and the downwardly bent side flanges of the top, nuts 64 being received over the threaded end of the screws for clamping the 100 upper ends of the side walls and downwardly extending flanges together. The corners of the top are provided with recesses 66, 67, through which the connecting posts between superposed units are received.

105 The rear end of the drawer forms a closed rear wall for the unit, and the front end of the drawer forms a closed front wall for the unit. When the drawer is closed, the upper end of the rear wall is received against the downwardly extending rear flange 55 of the top, and the upper end of the front wall of the drawer is received in the rabbet 69 at the front end of the top formed by the rearwardly extending flange 57 and the downwardly extending flange 58. The inside of the top adjacent to its front end is provided with a downwardly extending flange 71 110 preferably formed on a metal strip 72 suitably secured to the under face of said top, 115 as by means of being spot welded thereto, as indicated by the spot-welds 73.

120 When the drawer is closed, the side walls form closed sides for the unit, the top forms a closed top for the same, the rear wall of the drawer forms a closed rear end for the same, and the front wall of the drawer forms a closed front for the space within the unit. The outside side surfaces 74 of the drawer are received closely against the 125 130

inner faces of the front and rear curled ends of the side walls. The closed bottom of the drawer, received over the laterally extending wings of the runways for the same, 5 forms a closed lower end for said unit in connection with said runways.

Foot-pieces 76 are received over the lower posts 27 for forming feet on which the stack of units is supported. These feet preferably comprise a comparatively short piece 10 of metal, in which a hole 77 is bored lengthwise of the foot-piece, the downwardly extending lowermost posts at the respective corners of the lowermost unit being respectively received in the holes of these foot-pieces. 15

With my improved construction the acquiring of filing space may be begun by the acquisition of a single unit, which may be 20 arranged to be shipped in knock-down form, so as to minimize the expense of carriage. This knock-down unit may consist of two side walls, having the runways thereon, a pair of cross-bars having the posts extending 25 up and down therefrom, foot-pieces, and a top.

In assembling the unit the cross-bars have their downwardly extending posts pushed into the foot-pieces, the respective socket 30 ends of the side walls having their lower ends assembled over the upwardly extending posts of said cross-bars, the top then being put in place, preferably with the downwardly extending side flanges thereof received inside the side walls of the unit, the latter side walls and said downwardly extending flanges being connected by the screws and nuts. The framing is thereby 35 made ready for use, the drawer being slipped into the unit along the runways. 40

In slipping in the drawer the front end of the drawer is tilted upwardly, so that the upper end of its rear wall is received behind the downwardly extending flange 71 at the 45 front end of the inside of the unit, the drawer being then pushed rearwardly. If desired, cross-pieces having downwardly extending posts may be received across the front and rear ends of the upper portion of 50 the unit, with said downwardly extending posts received in the upper ends of the curled forward and rear ends of the side walls for additionally holding the parts together, although I have found in practice 55 such upper end connection is not essential.

If it is desired to superpose another unit on top of the unit previously formed, cross-bars 25, provided with upwardly extending posts 26 and downwardly extending 60 posts 27 are placed across the top of the front and rear portions of the unit previously formed, the downwardly extending posts being received in the sockets in the upper end of the previously formed unit. 65 The additional side walls are then received

over the upwardly extending posts at the respective front and rear ends of the unit, forming the side walls for the superposed unit, a top being secured to the upper ends of said side walls as previously described. 70

When the units are stacked, additional connecting means may be provided, connecting the rear ends of superposed units, exemplified as a plate 80 having lugs 81 struck up therefrom. These lugs are spaced from 75 the plate and are preferably parallel with the plate. The side walls are, at the rear portions of their upper and lower ends, provided with outwardly struck lugs 82, which are preferably spaced from said side walls 80 and parallel with said side walls. The lugs 81 of the connecting plate are received behind the lugs 82 at the proximate edges of superposed units, with the plate extending past the joint between the units, and hold the 85 units to prevent a tilting between the rear ends of the same, for instance, when a weighted drawer is pulled out. The connecting means are located in the space between the front and rear socket ends of the 90 side walls.

It may be desirable to connect stacks of units located side by side, or arranged back to back. I provide ready means for connecting the same, shown exemplified as connecting strips 84, the respective ends of which have separated apertures 85, 86, formed therein. The aperture 86 is exemplified as a slot forming a hook-end 87. These connecting strips are thin strips of sheet-metal, 100 which may in fact be as thin as a thirty-second of an inch, as the tensile strength of metal of this character is great. The posts of laterally adjacent sections or of sections arranged back to back, are received through 105 the apertures in the connecting strips, thereby tying the neighboring stacks of units together.

The connecting strips are shown located on the tops of the cross-bars, with the upwardly extending posts extending therethrough. The strips may be connected with the first stack of units formed by passing the posts through the apertures 85, and may, until a neighboring stack of units is formed, 110 be swung inwardly to place their hook ends in front of the laterally extending wings 38 of the runways, so as to be out of the way until used for connecting adjacent units. When the neighboring stack of units 115 is formed, these strips may be swung outwardly on their posts for having the posts of a neighboring stack of units received through the apertures in the outwardly swung ends of said strips, the hook-ends being swung about the latter posts. 120

This forms a ready means for connecting adjacent stacks of units and avoids the presence of spaces or cracks to admit dust or dirt. 125

I have in Fig. 8 shown an arrangement whereby adjacent stacks of units located side by side and back to back may be connected, connecting strips connecting the posts of laterally adjoining units and of units arranged back to back.

My invention provides ready and economical means of few parts whereby rigid units may be formed, whereby units may be superposed in rigid relation to resist strains in any direction, and whereby adjacent stacks of units may be readily connected.

Having thus fully described my invention, what I claim as new and desire to secure by Letters Patent, is:

1. A metal filing case unit comprising sheet-metal side walls provided with upright end socket bends, a cross-bar, and posts having connection with said cross-bar and received in the bores of said upright end socket bends.

2. A metal filing case unit comprising sheet-metal side walls provided with upright end socket bends, a cross-bar, posts having connection with said cross-bar and received in the bores of said upright end socket bends, and a top member having connection with said side walls.

3. A metal filing case comprising units arranged to be superposed, said units comprising upright side walls having upright socket bends at their ends, cross-bars, and posts extending up and down above and below said cross-bars and received in the bores of superposed socket bends.

4. A metal filing case comprising units arranged to be superposed, said units comprising side walls having upright end socket bends, a cross-bar, said side walls provided with recesses at said socket bends for receiving said cross-bar, and posts extending up and down above and below said cross-bar and received in the bores of superposed socket bends.

5. A metal filing case unit comprising sheet-metal side walls having upright socket bends at their front and rear ends, a cross-bar between the front ends of said side walls, a cross-bar between the rear ends of said side walls, posts extending from said cross-bars into said respective socket bends, and a top-member having connections with said side walls.

6. A knock-down metal filing case unit comprising sheet-metal side walls having upright socket bends at their front and rear ends, a pair of cross-bars arranged to be respectively received between the lower portions of the front and rear ends of said side walls, said cross-bars provided with posts at their respective ends arranged to be releasably received in the bores of said socket bends, a top-member, and releasable connecting means between said top-member and the upper portions of said side walls.

7. A metal filing case comprising units, said respective units comprising sheet-metal side walls having upright socket bends at their ends, cross-bars between superposed side walls, and posts having connections with said cross-bars and extending up and down from said cross-bars and received in the bores of said socket bends.

8. A metal filing case comprising units, said respective units comprising sheet-metal side walls having upright sockets at their ends, said side walls provided with recesses at said socket ends, cross-bars between superposed side walls received in said recesses, and posts having connections with said cross-bars and extending up and down from said cross-bars and received in said sockets.

9. A metal filing case comprising units, said respective units comprising a pair of sheet-metal side walls having upright socket bends at their ends, cross-bars between superposed pairs of side walls, posts having connections with said cross-bars and extending up and down from said cross-bars and received in the bores of said socket bends of superposed pairs of side walls, top-members between the upper ends of said side walls of said respective pairs of side walls, and means for rigidly connecting said top-members and said side walls.

10. A metal filing case unit comprising sheet-metal side walls provided with upright curled ends, a cross-bar between said side walls, posts rigid with said cross-bar and received in said curls, and runways for drawers fixed to said side walls and arranged to rest on said cross-bar.

11. In a metal filing case, the combination of adjacent stacks of superposed units, said respective units comprising sheet-metal sides having upright end socket bends, a cross-bar, and upright posts having connections with said cross-bar and received in the bores of said socket bends, and connecting strips between adjacent stacks of units through which said posts are received for connecting adjacent stacks.

12. In a metal filing case, the combination of adjacent stacks of superposed units, said respective units comprising sheet-metal sides having upright socket bends at their ends, cross-bars, and upright posts having connections with said cross-bars and received in the bores of said socket bends, and connecting strips arranged to have said posts received therethrough for connecting adjacent stacks arranged selectively side by side and back to back.

13. In combination, a metal filing case unit comprising sheet metal side walls having upright curls at their front and rear ends, cross-bars between said ends, posts extending from said cross-bars into the bores of said respective curls, said side walls pro-

vided with drawer runways extending toward each other, and a top-member secured to said side-walls for forming a unit with open front and rear ends, and a drawer arranged to be moved on said runways, said drawer provided with a rear wall and a front wall, said top-member provided with a depending rear flange with which said rear wall coacts to close the rear end of said unit, and said top-member provided with a depending front flange with which said front wall coacts to close the front end of said unit.

14. A metal filing case comprising units arranged to be superposed, said units comprising side walls having upright end socket bends, a cross-bar, posts extending up and down above and below said cross-bar and received in the bores of superposed socket bends, and connecting means extending up and down between proximate superposed units, the proximate portions of superposed side walls of said superposed units

and said connecting means provided with coacting retaining parts to connect said superposed units in up and down relation. 25

15. In a metal filing case, the combination of adjacent stacks of superposed units, said respective units comprising sheet-metal sides having upright end socket bends, a 30 cross-bar, upright posts having connections with said cross-bar and received in the bores of said socket bends, and a connecting hook between adjacent stacks of units provided with a pivot-aperture in which a post of one 35 of said stacks is received, and a hook-end arranged to be received about a proximate upright post.

In testimony whereof I have hereunto signed my name in the presence of two sub- 40 scribing witnesses.

FRANK A. SANDMANN.
